(57) **CLAIM**

The ornamental design for a vacuum flask, as shown and described.

DESCRIPTION

Fig. 1.1 is a front perspective view of my new design; Fig. 1.2 is a front view thereof; Fig. 1.3 is a back view thereof; Fig. 1.4 is a top plan view thereof; Fig. 1.5 is a bottom plan view thereof; and Fig. 1.6 is a right side view thereof, the left side view being a mirror image thereof.
 The broken lines and areas within them depict portions of the vacuum flask that form no part of the claimed design.
